ABSTRACT OF THE DISCLOSURE

A method and apparatus for detecting the presence of a relatively small hole in a workpiece, such as a bullet casing, by passing a slender detect pin through the hole. If the hole is obstructed or non-existent, the pin abuts the workpiece which terminates, prematurely, advancement of the pin. A sensing device is provided and is responsive to premature termination of the pin advancement to control a machine performing various operations on the member. Absence of the hole in the member is employed to stop the machine and enables the defective workpiece to be removed. Additionally, the device includes a safety feature by which, in the event that the slender, fragile pin breaks, the breakage will be sensed also to stop the machine. This enables the broken pin to be replaced and insures that the damaged pin will not permit any defective workpiece having no hole to pass through the detecting station to subsequent operating stations in the machine.

BACKGROUND OF THE INVENTION

This invention relates to a method and apparatus for detecting the presence of a hole in a workpiece and, more particularly, to a technique employed in quality control for the mass-production of bullet cartridge casings.

An essential part of a conventional bullet casing is the fire hole, located in the rear end of the casing, which communicates the main charge with the primer cap at the rear end of the casing. In the finally assembled cartridge, the fire hole must be clear in order for the cartridge to function properly. Such cartridges are manufactured in multi-station machines which perform a variety of operations on the casing such as to punch the fire hole in the casing, check the presence of the punched hole, debur the hole, and insert and seal the primer cap into the rear end of the casing. This invention relates to an improved technique for detecting the presence or absence of the punched fire hole.

Currently employed techniques for checking the presence of the fire hole include the use of a probe having a slender, needle-like pin which is passed through the hole of the casing. If the fire hole is present, the movement of the probe is uninterrupted during its insertion into and retraction from the fire hole. If the casing does not have a fire hole or if the fire hole is obstructed, the advancement of the probe is interrupted prematurely. The premature interruption is sensed by an appropriate switch which, in turn, controls the machine's circuitry to shut the machine off. The defective casing then is removed.

Because the fire holes are relatively small, the probes also are small and may tend to break, thus rendering the device ineffective in detecting the fire hole. This, in turn, permits defective casings having no fire hole to pass through the detection station to the subsequent operating stations in the machine.

This invention provides a detection device which not only causes the machine to stop when a defective cartridge is detected but which also causes the machine to stop if the detection probe or pin itself breaks or becomes damaged.

SUMMARY OF THE INVENTION

The device is mounted in the multi-station machine at a detect station. The machine includes a cross head which is movable heightwise toward and away from the casings supported on a conveyor below. The casings are supported in a vertical attitude on the conveyor which transports the casings past the various operating stations in sequence. The various operating devices, including the detection device, are mounted to the cross head and move downwardly toward the casings in a gang-like manner to perform their various operations in unison on the series of cartridges located below the cross head.

In brief, the detection device includes a slender, downwardly projecting probe which moves in unison, vertically, with the cross head. The probe additionally is mounted for vertical movement in relation to the cross head. Vertical movement of the probe in relation to the cross head actuates a switch which controls the chain to shut it off. Thus, when a casing having a fire hole is positioned below the probe, the pin of the probe will pass freely through the hole and then will be retracted upwardly in unison with the cross head. There is no relative movement of the probe in relation to the cross head. If, however, the casing does not have a properly formed fire hole, the downward advancement of the probe will be terminated prematurely when it abuts the casing. The cross head, however, continues its downward movement, thus effecting the relative heightwise movement of the probe and cross head which, in turn, shuts the machine off.

In the event that the slender pin becomes broken, the detection device includes an expandable element which extends downwardly of the broken pin immediately after and in response to breakage of the pin. When expanded, this element projects downwardly from the probe a distance sufficient so that when the probe and cross-head are urged downwardly toward the casing, the lower end of the expanded element will engage the casing prematurely. Continued downward movement of the cross-head will actuate the sensing mechanism and stop the machine. The operator then may replace the broken probe.

It is among the primary objects of the invention to provide an improved fire hole detection technique which reduces the likelihood of failure to detect a defective cartridge.

A further object of the invention is to provide an improved fire hole detection method and apparatus which senses the existence of the fire hole and also detects malfunction of the detection device.

Still another object of the invention is to provide a method and apparatus for sensing the presence of a fire hole in a cartridge casing which is effective to shut off the machine in response to the presence of a defective cartridge casing or a defect in the detection device itself.

DESCRIPTION OF THE DRAWINGS

These and other objects and advantages of the invention will be understood more fully from the following detailed description thereof, with reference to the accompanying drawings wherein:

FIG. 1 is a sectional elevation of the detection device as mounted to the cross head of the multi-station machine;

FIG. 2 illustrates the operation of the device when testing a properly formed cartridge;

FIG. 3 illustrates operation of the device testing the cartridge having no fire hole;

FIG. 4 is an illustration of the device in which the detection pin has been broken and which illustrates the manner in which the device actuates the control circuit in response to breakage of the pin; and

FIG. 5 is a sectional view through the detection pin as seen from the plane 5—5 of FIG. 1.

DESCRIPTION OF THE PREFERRED EMBODIMENT

As shown in FIG. 1, the detection device is mounted to the cross head 10 of the machine. The cross head 10 is located directly above a conveyor 11 (see FIG. 2) which supports the cartridges for advancement below the cross head 10, so that the cartridges on the conveyor may be presented, sequentially, to the various operating devices mounted to the cross head 10. The conveyor 11 may include a plurality of cartridge supporting posts 13 which support the cartridge 15 in a vertical attitude with the head of the cartridge facing upwardly. In the illustrative embodiment the cartridge includes a recess 17 in the head to receive the primer cap (not shown). The fire hole 19 is formed in the cartridge head and communicates the recess 17 with the interior of the cartridge 15. The detection device includes a cylindrical probe body 12 which is supported by the cross head 10 for vertical, sliding movement within the hole 14 formed in the cross head. The lower end of the probe body is formed to define an enlarged collar portion 16 which also defines the shoulder 18. A top retaining ring 20 surrounds the probe body 12 and rests on the shoulder 18. The ring 20 is fastened to this position by a set screw 22.

The probe body 12 is biased in the most downward position shown in FIGS. 1 and 2 by means of a coil spring 24 which surrounds the lower end of the probe body and extends between the underside of the cross head 10 and the upper surface of the top retaining ring 20.

The heightwise position of the probe in relation to the cross head is adjustable by means of a nut 26 which is threaded about the upper end of the probe body 12, and which rests on the upper surface of the cross head 10.

The upper end of the probe body also includes an upwardly extending microswitch trip member 28 which may have a conical surface formed about its upper end. The microswitch trip member 28 has a lower shank 30 which is threaded into a hole formed in the upper end of the probe body 12 to permit the relative height between the trip member 28 and probe body 12 to be adjusted. Once adjusted to the desired relative height, the trip member 28 is locked in position by the lock nut 32.

The detection device also includes a microswitch 34 which is mounted securely to the cross head 10 for actuation by upward movement of the probe body 12 and trip member 28 in relation to the cross head 10. As described below, the microswitch 34 is incorporated into the circuit of the machine to shut the machine off when actuated.

The lower end of the probe body 12 receives and supports the detection pin 36. The pin 36 is received and secured within a central bore 38 formed in the probe housing 12 by the set screw 40. The lower, downwardly projecting tip of the detection pin 36 is tapered to a slender shape which may be passed through the fire hole 19 in the casing 15 being tested.

In operation, the cartridge casing 15, as shown in FIG. 2, is positioned by the conveyor directly below the detection device with the head end of the casing 15 facing upwardly toward the detection device. The cross head 10 then is moved downwardly to advance the various operating devices, including the detection device, downwardly toward and into engagement with their respective cartridge casings supported below. If the fire hole 19 is formed properly in the casing 15, the slender, lower end of the detection pin 36 will pass freely into and through the fire hole 19. The cross head 10 then is raised upwardly to the idle position to enable the conveyor to advance one operating station, thus presenting each cartridge on the conveyor to the next operating station in the machine. Thus, when the fire hole 10 is formed properly within its cartridge casing 15, the cross head 10, detection device and microswitch 34 move in unison. There is no relative

heightwise movement of the probe body 12 to the cross head 10 and the microswitch 34 thus remains unactuated.

If, however, as shown in FIG. 3, the cartridge casing 15 did not have a properly formed fire hole 19, then the lower end of the detection pin 36 would abut the head end of the cartridge casing thus terminating prematurely the downward movement of the probe body 12. The cross head 10 and microswitch 34, however, would continue to advance downwardly in relation to the stationary probe body 14 and microswitch trip 28. This actuates the microswitch 34, which, in turn, stops operation of the machine and enables the defective cartridge to be removed.

As mentioned above, because of the relatively slender and fragile construction of the lower end of the detection pin 36, it is not uncommon for the detection pin to break, as when subjected to excessive shear or compressive stresses. In order to obtain the high degree of quality control necessary in fabricating bullets, any such malfunction of the detection device should be corrected immediately so that no defective casings are passed to subsequent operating stations. In accordance with the invention, the lower end of the detection device includes an arrangement by which breakage of the lower end of the detection pin 36 will result in actuation of the microswitch 34 thus shutting off the machine.

As shown in FIGS. 1 and 4, the safety arrangement for detecting pin breakage includes a detection pin bushing 46 which is retained, slideably, within an enlarged concentric bore 48 formed at the bottom of the probe body 12. The bushing 46 has a longitudinal hole formed therethrough which receives the lower end of the detection pin 36. A bottom retaining ring 50 having an upturned peripheral flange 52 is located at the underside of the probe body 12. The retaining ring 50 has a central hole which registers with the enlarged bore 48 and which receives the lower end of the detection pin bushing 46. The lower end of the detection pin bushing which projects downwardly beyond the bottom retaining ring 50 has a shoulder 54 formed thereon which receives and grips the retaining ring 50 between it and the bottom surface of the probe body 12. These parts are maintained in this arrangement by means of a cotter pin 56 which is passed through a transverse hole 58 formed in the lower, protruding end of the detection pin 36. A relatively heavy compression spring 60 is provided which surrounds the collar portion 16 of the probe body 12 and which bears against the underside of the top retaining ring 20 and the upper surface of the bottom retaining ring 50. When the device is assembled in the configuration shown in FIG. 1, the spring 60 is in a compressed state so that if the cotter pin 56 is released (as when the lower tip of the detection pin 36 ruptures) the spring 60 will expand and will drive the bottom retaining ring 50 and the bushing 46 downwardly to the position shown in FIG. 4.

The extent of downward movement of the bottom retaining ring 50 and detection pin bushing 46 is limited by a slot 62 formed along one side of the bushing 46. A stop screw 64 is threaded transversely through the collar portion 16 of the probe body 12 and protrudes into the slot 62, thus limiting the extent of downward movement of the bushing 46 when the upper end of the slot 62 engages the inner end of the stop screw 64. The bushing 46 is precluded from rotating within its receptive bore 48 by means of a flat 66 formed on the opposite side of the bushing which cooperates with the set screw 68 threaded through the collar portion 16 of the probe body 12 and which bears lightly against the flat 66.

FIG. 4 shows the configuration of the device when the lower end of the detect pin 36 has been broken and the cotter pin 56 is released from its locking position. Once the cotter pin 56 has been released the compression spring 60 forces the bottom retaining ring 50 and bushing 46 to expand downwardly until the upper end of the slot 62 engages the stop screw 64. This effectively extends the lower surface of the bushing 46 in relation to the probe

to the level at which the lower tip of the detection pin extended.

When the broken detection device is urged downwardly toward a cartridge casing, as shown in FIG. 4, the expanded broad bottom surface of the detection pin bushing 46 will abut the end of the casing before the cross head 10 has reached the full downward limit of its travel. With downward advancement of the probe body 12 thus interrupted, continued downward advancement of the cross head 10 causes the microswitch 34 to engage the microswitch trip member 28 on the probe body 12 and stop the machine.

Because of the relatively small dimensions of the fire hole 19 and the correspondingly small dimensions of the tapered lower tip of the detection pin 36, it is important that these elements be in registry before the cross head 10 brings the detection device downwardly toward and into engagement with the cartridge casing. If the tip of the detection pin 36 is bent or is otherwise deformed so that it cannot pass freely into and out of the fire hole it is essential that this condition be corrected immediately in order to insure that defective casings are not passed through to the following stations in the machine. In the instant invention, this is accomplished by providing a weak portion in the lower end of the detection pin 36 which will fracture when any abnormal load is imposed on it. This weakened region is provided by the relatively thin sidewalls 70 which are defined by the transverse hole 58 in the detection pin 36 through which the cotter pin 56 is passed. The detection pin 36 will rupture at the 30 weakened sidewalls 70 in response to excessive loads. As described above, this releases the cotter pin 56 and permits the bottom retaining ring 50 and bushing 46 to expand downwardly under the force of the spring 60. This, in turn, causes premature termination of downward movement of the probe which triggers the microswitch 34 as described above.

It should be understood that the foregoing description is intended merely to be illustrative of the invention and that other embodiments and modifications thereof may be apparent to those skilled in the art without departing from its spirit. For example, although the invention has been described as being useful primarily in connection with the testing and detection of fire holes formed in bullet cartridges, it may be employed with equal effectiveness in almost any environment which it is desirable to check the presence or accurate formation of a hole formed in a workpiece, particularly when the hole is relatively small. Furthermore, although the invention is particularly useful in multi-station machines which perform a number of operations on a work piece, it may be employed as a single station device if desired.

Having thus described the invention, what is claimed is:

1. A device for detecting the presence of a hole in a workpiece comprising:
a probe unit having a pin dimensioned to be passed through said hole;
means for supporting said workpiece in predetermined position in relation to said probe unit;
means mounting said probe unit for movement along a path that is toward and away from said supported workpiece and in a stroke such that said probe may pass through said hole and then be retracted out of said hole, said portion of said stroke that is toward said member being terminable, prematurely, by engagement of said pin with a member having no hole;
means responsive to said premature termination of advancement of said probe unit for signalling the absence of said hole in said member; and
means responsive to breakage of said pin for effecting premature termination of advancement of said probe unit.

2. A device as defined in claim 1 wherein said means mounting said probe unit for said movement comprises: a support member disposed above and movable toward

and away from said supported workpiece whereby said probe may be advanced toward and away from said workpiece in unison with said support member; means mounting said probe to said support member for height-wise movement in relation thereto whereby when said advancement of said probe is terminated prematurely, said support member may continue and complete its downward stroke; and said means responsive to said premature termination of advancement of said probe unit comprising means responsive to said relative heightwise movement of said probe and support means.

3. An apparatus as defined in claim 2 wherein said means responsive to said pin breakage for effecting said premature termination of probe advancement comprises: means for expanding the effective length of said probe in response to said pin breakage.

4. An apparatus as defined in claim 3 wherein said probe unit comprises:
a probe body mounted to said probe support member for said heightwise movement in relation thereto; a detection pin mounted to said probe body and having a lower end projecting downwardly from said probe body;
said means for expanding the effective length of said probe comprising:

a bushing slideably mounted to the lower end of said probe body for movement along and axially of said pin, said pin passing through said bushing;

means biasing said bushing in a downward direction; and

means releasably restraining said downward movement of said bushing so that when released, said bias means will urge said bushing downwardly in relation to said probe body to expand the effective length thereof.

5. An apparatus as defined in claim 4 wherein said means for releasably restraining said downward movement of said bushing comprises:

a transverse pin passing through a hole formed in the lower end of the probe pin, the bottom end of said bushing bearing downwardly against said transverse pin.

6. An apparatus as defined in claim 5 wherein the wall defined by said hole is relatively weak whereby any excessive stresses imposed on said pin will cause said pin to rupture about said hole thereby releasing said transverse pin.

7. An apparatus as defined in claim 4 wherein said means biasing said bushing in a downward direction comprises:

an upper retaining ring secured to and about the probe body;

a lower retaining ring at the bottom of said probe body and having a central hole formed therein, said bushing extending downwardly through said central hole and said lower retaining ring, said bushing having a shoulder to support said lower retaining ring; and a compression spring extending between the upper and lower retaining rings.

8. An apparatus as defined in claim 7 wherein said means for restraining said downward movement of said bushing comprises:

a transverse pin passing through a hole formed in the lower end of said probe pin, the lower end of said bushing bearing downwardly against said transverse pin.

9. An apparatus as defined in claim 4 further comprising:
means limiting the extent of downward movement of said bushing in relation to said probe body.

10. An apparatus as defined in claim 9 wherein said means limiting said downward movement of said bushing comprises:

a slot formed along the length of said bushing; and a stop member secured to said probe body and extending into said slot whereby engagement of the ends of said slot with said stop member limits the extremities of movement of said bushing.

11. An apparatus as defined in claim 10 further comprising:

means precluding rotation of said bushing about its longitudinal axis axis including a flat formed on and along the side of said bushing and a guide member secured to said probe body and extending inwardly toward said flat, said guide bearing slideably against said flat.

12. A method for detecting the presence of a hole in a workpiece comprising:

providing a probe having a slender pin extending therefrom;
advancing said probe toward said member so that when said member has a hole formed therein, said probe will pass through said hole to a predetermined extent;
retracting said probe and said pin therefrom from said hole;
whereby in the event said member does not include said hole said advancement of said probe toward said member will be terminated prematurely;

signalling the absence of said hole in response to said premature termination of advancement of said probe; and effecting an identical signal in response to breakage of said pin portion of said probe.

13. A method as defined in claim 12 wherein said step of effecting said signal in response to breakage of said probe comprises:

expanding the effective length of said probe along the direction of advancement thereof toward said workpiece whereby advancement of said probe having a broken pin will be terminated prematurely by reason of engagement of the expanded portion of said probe with said workpiece.
